WELL DRILL

Jesse C. Wright, Los Angeles, Calif.

Application October 6, 1934, Serial No. 747,188

5 Claims. (Cl. 255—61)

This invention relates to a well drilling tool and relates more particularly to a well drill for use in the rotary method of drilling. A general object of the invention is to provide a simple, practical and effective rotary well drill adapted for the enlarging of pilot bores.

Another object of the invention is to provide an effective and dependable means for locking a replaceable cutter head or bit on the shank of a well tool.

Another object of the invention is to provide a well drill including a pilot bit threaded on a shank and a simple, convenient means for locking the pilot bit against unthreading from the shank.

Another object of the invention is to provide a well drill of the character mentioned comprising a pilot bit for entering a pilot hole or bore and a reaming cutter for enlarging the bore, said bit and cutter being formed and related to drill or form an enlarged bore that is straight and vertical.

A further object of the invention is to provide a well drill of the character mentioned that is inexpensive of manufacture and that embodies a simple, one piece shank.

The various objects and features of my invention will be fully understood from the following detailed description of a typical preferred form and application of the invention, throughout which description reference may be made to the accompanying drawing, in which:

Fig. 1 is a side elevation of the drill of the present invention, operating in a well bore, illustrating one quarter in longitudinal cross section. Fig. 2 is a transverse detailed sectional view taken as indicated by line 2—2 on Fig. 1. Fig. 3 is a bottom elevation of the drill and Fig. 4 is a transverse detailed sectional view taken as indicated by line 4—4 on Fig. 1, illustrating the means for locking the pilot bit onto the shank.

The drill of the present invention includes, generally, a shank 10, a pilot cutter or pilot bit 11 on the lower end of the shank, means 12 for locking the pilot bit 11 against detachment from the shank 10, and a bore enlarging or reaming cutter 13 on the shank 10 above the pilot cutter 11.

The shank 10 is provided to carry the pilot bit 11 and the reaming cutter 13 and in accordance with the invention may be a simple one piece or integral member. The shank 10 may be comparatively long and may be generally cylindrical. Suitable means is provided at the upper end 55 of the shank 10 for facilitating its connection

with the drilling string. In the particular construction illustrated in the drawing a tapered screw-threaded pin 14 is provided on the upper end of the shank 10 to connect the shank with the string. An annular enlargement or flange 15 is provided on the shank 10 at some distance below its upper end. The lower end or face of the flange 15 forms an annular downwardly facing shoulder 16. A suitably tapered threaded portion 17 is provided on the shank 10 below the shoulder 16 to carry the cutter 13. The lower portion 18 of the shank occurring below the threaded portion 17 is of reduced diameter and may be stepped or graduated as illustrated in Fig. 1 of the drawing. A tapered screw-threaded pin 19 projects from the lower end of the shank 10 to carry the pilot bit 11. A downwardly facing annular shoulder 20 is provided at the upper end of the pin 19. In the preferred construction the pin 19 has a plain or unthreaded portion 21 between the shoulder 20 and its thread.

The pilot cutter or pilot bit 11 is adapted to operate in a previously formed pilot hole or bore B to guide the drill whereby the reaming cutter 13 enlarges the bore to provide a straight vertical well bore W of the desired diameter. It is to be understood, of course, that the pilot bit 11 may be operated to drill into the formation to form its own pilot bore B. The pilot bit 11 includes a shoe or body 22 having a threaded socket 23 receiving the pin 19 of the shank. The pilot bit body 22 is adapted to be threaded on the pin 19 to a position where its upper end bears upwardly against the shoulder 20. The upper end portion of the socket 23 which surrounds the shank portion 21 is preferably plain or unthreaded. The bit body 22 may have a downwardly tapering periphery and lower end.

The pilot bit 11 includes guiding and cutting parts adapted to engage the wall of the pilot bore 40 B to guide the drill, said cutting parts being operable to drill a pilot bore when a previously formed pilot bore has not been drilled. The guiding and cutting parts of the pilot bit 11 are preferably in the form of blades 24 projecting 45 downwardly from the lower end of the bit body 22 and projecting radially outwardly from the body. In the particular construction illustrated in the drawing there are four equally spaced blades 24 provided on the pilot bit. The blades 50 24 are preferably comparatively long to extend downwardly from adjacent the upper end of the body 22 to points some distance below the lower end of the body. The blades 24 have straight substantially vertical reaming and guiding edges 55

25 for engaging the wall of the pilot bore. The long reaming and guiding edges 25 of the circumferentially spaced blades 24 effectively stabilize and guide the drill. The lower ends of the blades 5 24 are formed and shaped to effectively drill through the formation when the drill is operated to form its own pilot bore, and when the pilot bit 11 reaches the lower end of a previously formed pilot bore. The lower end portions of the blades 10 24 are curved forwardly relative to the direction of rotation of the drill and have suitable cutting edges 26.

The lower end portions of the blades 24 are notched or provided with upwardly extending notches. There is preferably one notch provided 15 in the lower edge of each blade 24 at a point spaced between the inner and outer ends of the blade. The notches 27 in one pair of diametrically opposite blades 24 are closer to the central longitudinal axis of the drill than the notches 28 in the other pair of diametrically opposite blades. The notches 27 separate or divide the lower portion of the first mentioned blades 24 into outer teeth 29 and inner teeth 30. In a like 20 manner the notches 28 in the said other blades 24 divide the lower portions of the blades into outer teeth 31 and inner teeth 32. The inner teeth 30 extend inwardly to join one another at the central longitudinal axis of the drill to cut 25 away the formation at the center of the bore. The inner teeth 32 of the other blades are spaced from the central longitudinal axis of the drill to act on the formation in the path of the notches 27. The outer teeth 29 are preferably of sufficient width to cut away the formation left by the notches 28. The cutting blades 24 formed and related as just described are particularly rapid and efficient in operation when the drill is operated to form its own pilot bore.

40 Under some conditions of operation the previously formed pilot bore B may have an enlarged portion. When the pilot bit 11 enters such an enlarged portion in the pilot bore B the drill may develop a whipping or gyroscopic motion, 45 particularly where the reaming cutter 13 has a tendency to chatter or run roughly. The whipping of the tool under such conditions may cause the pilot bit to become unthreaded from the shank 10 if means is not provided for locking it 50 on the shank. The means 12 embodied in the present invention is provided to dependably lock the pilot bit 11 against unthreading and detachment from the shank under all operating conditions. It is a feature of the invention that the 55 lock means 12 is such that the pilot bit 11 may be easily threaded on the pin 19 to a position where its upper end clamps against the shoulder 20 and may then be quickly locked in the desired position.

60 The lock means 12 includes or provides a plurality of circumferentially spaced sockets 33 in the pin 19. In practice it has been found desirable to provide three equally spaced sockets in the pin of the shank. The sockets 33 are preferably provided in the unthreaded upper portion 65 21 of the pin, it being understood that the sockets may be provided at other points in the pin if desired or found practical. The lock means 12 further provides openings 34 in the wall of the pilot bit body 22. The openings 34 are circumferentially spaced in a horizontal plane and are located so that they are in the same horizontal plane as the sockets 33 when the upper end of the bit body 22 is engaging or is immediately 70 adjacent the shoulder 20.

In accordance with the invention the openings 34 are related to the sockets 33 so that one of them will register with a socket 33 when the bit body 22 is in any possible rotative position on the pin 19 with its upper end engaging or adjacent the shoulder 20. This relationing of the openings 34 to the sockets 33 is preferably accomplished by horizontally elongating the openings and by providing more openings 34 than there are sockets 33. Thus where there are three 10 sockets 33 it may be desirable to provide four equally spaced horizontally elongated openings 34. The horizontal length of the openings 34 is sufficient to insure the registration of one of the openings with a socket 33 when the pilot bit 15 11 is threaded to the required position on the pin 19. By providing more openings 34 than there are sockets 33 it does not become necessary to horizontally elongate the openings 34 to such an extent as to materially weaken the bit body 22. 20

A lock member 35 is adapted to be inserted in the exposed socket 33 to extend into the registering opening 34 to lock the pilot bit 11 against unthreading from the shank 10. In the simple preferred form of the invention illustrated in the 25 drawing the sockets 33 are threaded and the lock member 35 is in the form of a screw adapted to be threaded into the exposed socket 33 to project into the registering opening 34. The set screw or lock member 35 is proportioned so that its head 30 or outer projecting portion is entirely within the opening 34. The outer portion or head of the lock member 35 is provided with a polygonal socket 36 to facilitate the threading of the member into the socket 33. The screw or lock member 35 35 threaded into a socket 33 and projecting into an opening 34 dependably locks the pilot bit 11 against unthreading from the shank 10 under all conditions of operation of the drill.

The bore enlarging or reaming cutter 13 is 40 removably attached to the shank 10 above the pilot bit 11 to act on the earth formation at the upper end of the pilot bore 11 and provide or drill the enlarged bore W. The reaming cutter 13 includes a body or shoe 37 threaded on the portion 17 of the shank to bear or clamp upwardly against the shoulder 16. Prior to the arrangement of the pilot bit 11 on the shank 10 the shoe 37 of the reaming cutter is adapted to be passed over the lower portion of the shank and 45 threaded on the shank portion 17. While I have not shown the reaming cutter 13 locked on the shank 10 it is apparent that it may be locked in place by a means similar to the means 12 described above. The reaming cutter 13 includes 50 cutting parts in the form of blades 38 projecting from the shoe 37. There may be four circumferentially spaced blades 38 projecting downwardly and outwardly from the shoe 37. The blades 38 have lower cutting edges 39 which act 55 on the earth formation at the shoulder S between the pilot bore B and the enlarged bore W. The lower cutting edges 39 of the reaming blades may be straight and horizontal as illustrated in Fig. 1. The blades 38 are provided with comparatively 60 long reaming edges 40 for acting on the wall of the well bore W.

The drill is provided with means for handling the circulation fluid usually employed in the rotary method of well drilling. A central longitudinal fluid passage 41 extends through the shank from the upper end of the pin 14 to the lower end of the pin 19. The body 22 of the pilot bit has a chamber 42 at the lower end of the socket 23 to receive the circulation fluid from 70

the passage 41. Discharge openings or ports 43 are provided in the lower end wall of the bit body 22 to discharge the circulation fluid downwardly from the chamber 42. The ports 43 are preferably located to discharge into the well at points between the spaced blades 24.

It is believed that the operation of the well drill will be readily understood from the foregoing detailed description. When employed to 10 enlarge a previously drilled pilot bore B the pilot bit 11 enters the pilot bore and operates therein to guide the drill. The long reaming edges 25 of the pilot bit blades engage the wall of the pilot bore B to steady the drill during operation and 15 to guide the drill to make a vertical hole. As the shoulder S occurring between the pilot bore B and the enlarged portion W of the well bore may be comparatively narrow the reaming cutter 13 is rapid in its cutting action. The downwardly 20 feeding pressures or drill pressures applied to the drill are concentrated on the portions of the blades 38 acting on the shoulder S so that a high cutting pressure is exerted per lineal unit of the cutting edges 39. The circumferential spacing 25 of the blades 24 and the blades 38 insures the steady smooth operation of the drill. When the drill is employed to cut its own pilot bore the teeth 29, 30, 31 and 32 of the pilot bit blades 30 act on the formation at the bottom of the bore to drill the pilot hole. The spacing and relating of the teeth is such that they are rapid and effective in their drilling action. When the pilot bit 11 is employed to drill the pilot bore B the blades 38 of the reaming cutter enlarge the bore to the 35 desired size.

The means 12 for locking the pilot bit 11 on the shank 10 is simple and inexpensive and dependably holds the pilot bit against detachment. When attaching the pilot bit 11 to the shank it 40 may be freely threaded on the pin 19 to clamp upwardly against the shoulder 20 with the desired force. Because of the relationship between the sockets 33 and the openings 34 an opening 34 registers with a socket 33 regardless of the 45 rotative position assumed by the pilot bit when finally threaded on the pin 19. The lock member or set screw 35 may be threaded into the exposed socket 33 to project into the registering opening 34. The lock member 35 operates to prevent the 50 accidental or unintentional unthreading of the pilot bit from the shank. When it becomes desirable or necessary to remove the pilot bit 11 from the shank the lock member 35 may be unthreaded from the socket 33 whereupon the pilot bit may be 55 unthreaded from the pin 19 of the shank.

Having described only a typical preferred form and application of my invention, I do not wish to be limited or restricted to the specific form and application herein set forth, but wish to

reserve to myself any modifications or variations that may appear to those skilled in the art or fall within the scope of the following claims.

Having described my invention, I claim:

1. A well drill including a shank having circumferentially spaced sockets, a cutter threaded on the shank having circumferentially spaced openings one of which registers with a socket when the cutter is threaded to its position on the shank, and a lock member inserted in the 10 said socket to project into and cooperate with the said opening to lock the cutter against unthreading.

2. A well drill including a shank having circumferentially spaced sockets, a bit threaded on 15 the lower end of the shank having circumferentially spaced openings, one of which will register with a socket regardless of the rotative position of the bit when the bit is in its proper longitudinal position on the shank, and a lock member 20 adapted to be inserted in the said socket to project into the said opening to lock the bit against unthreading.

3. A well drill including a shank having circumferentially spaced sockets, a shoulder on the 25 shank, a cutter threaded on the shank to bear against the shoulder having a plurality of circumferentially spaced openings, one of which will register with a socket regardless of the 30 rotative position assumed by the cutter when bearing against the shoulder, and a screw threaded in the said socket to project into the opening registering with the socket to lock the cutter against unthreading.

4. A well drill including a shank having circumferentially spaced sockets, a bit threaded on 35 the lower end of the shank having circumferentially spaced openings, the openings being circumferentially elongated and related to the sockets so that one of them will register with a 40 socket regardless of the rotative position of the bit when the bit is in its proper longitudinal position on the shank, and a lock member adapted to be inserted in the said socket to project into the 45 said opening to lock the bit against unthreading.

5. A well drill including a shank having a threaded lower portion, a downwardly facing shoulder on the shank, there being a plurality of circumferentially spaced sockets in the shank adjacent the shoulder, a bit threaded on the lower 50 portion of the shank to bear upwardly against the shoulder, the bit having a plurality of circumferentially spaced openings one of which will register with a socket regardless of the rotative position assumed by the bit when bearing against 55 the shoulder, and a lock part threaded into said socket to extend into the said opening to lock the bit against unthreading.

JESSE C. WRIGHT.
